UNITED STATES PATENT OFFICE.

JOHN CHALLBERG, OF MARCY, IOWA.

WINDMILL.

SPECIFICATION forming part of Letters Patent No. 317,298, dated May 5, 1885.

Application filed May 24, 1883. (No model.)

To all whom it may concern:

Be it known that I, JOHN CHALLBERG, a citizen of the United States, residing at Marcy Township, in the county of Boone and State 5 of Iowa, have invented certain new and useful Improvements in Windmills, of which the following is a specification, to wit:

This invention relates to an improvement in windmills; and it consists in certain novel 10 peculiarities of construction and arrangement, whereby the speed of the wheel is automatically controlled, the blades thrown into or out of the wind, and the wheel started and stopped at will, substantially as will be hereinafter 15 more fully set forth.

In order to enable others skilled in the art to which my invention relates to make and use the same, I will now proceed to describe its construction and operation, referring to the 20 annexed drawings, in which—

Figure 1 is a perspective view of my invention; Fig. 2, a central vertical section of the same. Fig. 3 shows two views of the blade, and Fig. 4 a detail of part of the device for 25 regulating the fans.

A represents a windmill-tower of any suitable construction, which is capped by a metal ring, A', having an annular groove, a, upon its inner side, which receives a flange, b, upon 30 the periphery of a second ring, B, which forms the turn-table. In lugs b' upon this ring B is journaled the shaft C of the wind-wheel which is cranked just over the center of the tower and provided with a pitman, C', running down a suitable distance and jointed to the rod C', which passes down to the ground and is connected to any desired machinery. 35

Upon the shaft C is placed the wind-wheel, consisting of the radial arms D D, secured in 40 cast boxes d at the hub and connected at their outer ends by a ring or circle, d', and by a second ring, d'', at a suitable distance from the center, in this case about one-third. Between these two rings are pivoted the fan-blades D'.

These blades are formed of sheet metal, as 45 shown in Fig. 3, and are strengthened by a metal rod, d'', around their edges. They are pivoted in the rings d' d'', one-third of their width from the inner edge, thus enabling them 50 to be easily turned without regard to the strength of the wind, and causing the wind

when very strong to turn them automatically. They are all connected midway between the rings d' d'' by a third ring, d'', by which they are all controlled and moved at once.

Upon the shaft C, between the wheel and the tower, is arranged a loose sleeve, E, formed with an annular groove, e, provided with a collar, E', having arms e' extending forward and jointed to cranks e'' upon the inner ends 60 of rods E'', journaled on two of the arms D of the wheel, and having their outer ends cranked and secured to the ring d''. A U-shaped link, F, connects the sleeve or collar E with the shorter ends of a yoke-lever, F', fulcrumed on 65 the turn-table and provided with a weight, F'', upon its longer arm, which tends always to keep the collar at the inner end of its stroke and holds the blades in proper position to catch the most wind, while at the same time 70 any excess of pressure by a strong breeze will turn the blades and overcome the action of the weight. The short ends of the yoke-lever F' are also connected by links or rods f f with a sliding collar, G, adapted to slide vertically 75 upon the tube g, through which the operating-rod C' passes, and on this collar is pivoted at y, a yoke-lever, H, having one arm fulcrumed on the tower-frame x and the other provided with a cord, h, leading to the ground. It will 80 thus be seen that any person below may at any time control the speed of the wheel by pulling on this cord, which, by its intermediate connections, turns the fan-blades, and the wheel may be stopped altogether by the same 85 means. The outer end of the shaft C is provided with a four-bladed vane, I, arranged as shown, and these, being opposite the open center of the wheel, catch more of the wind, and are thus smaller and closer to the wheel than 90 is usual.

Having thus fully described my invention, what I claim as new, and desire to secure by Letters Patent, is—

1. In a windmill, the combination of the 95 pivoted blades, the movable ring d'', cranked arm E'', connected at one end to the iron ring d'' and at the other with a yoke capable of movement on the main shaft, and means, substantially as described, for moving said yoke, 100 substantially as shown and set forth.

2. A windmill consisting, essentially, of the

tower A, turn-table A' B, shaft C, connected to the pitman C', and wheel having radial arms D, rings d' d², and pivoted sheet-metal blades D', connected by a ring, d⁴, in combination with the rods E², cranked at both ends, collar E', having arms e' e', sliding grooved sleeve E, U-link F, weighted yoke-lever F', links f f', sliding collar G, yoke-lever H, and regulating rod or cord h, all constructed and

arranged to operate substantially as and for the purpose set forth.

In testimony whereof I affix my signature in presence of two witnesses.

JOHN CHALLBERG.
